UNITED STATES PATENT OFFICE.

MATHEW J. SHERIDAN, OF BLACKWELL, OKLAHOMA.

OBSTETRICAL INSTRUMENT.

1,295,219.

Specification of Letters Patent.

Patented Feb. 25, 1919.

Application filed October 9, 1917. Serial No. 195,569.

To all whom it may concern:

Be it known that I, MATHEW J. SHERIDAN, a citizen of the United States, residing at Blackwell, in the county of Kay and State of Oklahoma, have invented certain new and useful Improvements in Obstetrical Instruments; and I do hereby declare the following to be a full, clear, and exact description of the invention, such as will 5 enable others skilled in the art to which it appertains to make and use the same.

My invention relates to obstetrical instruments, and has for one of its objects the production of an instrument of this nature 10 for aiding in the parturition of the fetus of certain kinds of the viviparous animals, and is more especially designed for use in the delivery of sows that require artificial aid.

20 Another object of this invention is to provide an obstetrical instrument which can be safely and easily operated and which is provided with means for engaging the head of the fetus at a plurality of points to 25 thereby distribute the strains in a manner to prevent injury to the tender fetus.

Another object of this invention is to so construct the operating ends of the instrument that their extremities will closely 30 contact with each other and to provide the instrument with locking means for preventing the casual separation of the operating ends of the instrument until required to be separated.

35 Another object of this invention is to so attach certain of the ends of the cords or snares employed to one of the jaws of the instrument whereby to simplify the actuation of the cords or snares and avoid confusion which might result in one cord being 40 drawn tighter than the other and cause injury to the fetus.

Another object of this invention is to provide an instrument of this nature which is 45 light and simple in construction, efficient in operation and durable, and one that can be manufactured and sold upon the market at a nominal cost.

These and other objects and advantages 50 will more fully appear as the nature of the invention is more clearly understood from the following description taken in connection with the accompanying drawings wherein there is disclosed one embodiment 55 of the invention, but which is susceptible to numerous alterations and variations in

the form, construction and arrangement of the parts to meet the exigencies of the case without departing from the spirit of the invention or exceeding the scope of the 60 claims.

In the drawings:

Figure 1 is a perspective view of the instrument, showing the same in opened position.

Fig. 2 is a detail view of the operating end of the instrument, showing the operating jaws thereof in partially closed position with the cords or snares drawn partially 65 taut.

Fig. 3 is a similar view of Fig. 2, excepting, that this figure shows the cords or snares formed in loops.

Referring to the drawings, wherein similar reference characters denote corresponding parts throughout the several views, 1 and 2 indicate a pair of co-acting arms provided with the respective handles 3 and 4 and having their substantially central portions flattened laterally and bent transversely in opposite directions at spaced 70 points to provide the co-acting pivotal members 5 and 6 which are connected by the pivotal member 6'.

Formed upon the outer ends of the arms 85 1 and 2 respectively are the flattened co-operating jaws 7 and 8, the arms 1 and 2 being respectively bent in opposite directions as at 9 and 10 so as to deflect the opposing co-operating jaws 7 and 8 slightly 90 inwardly toward each other so that their outer ends will closely contact with each other when the jaws 7 and 8 are operated to closed position, and formed through the jaw 7 are the plurality of vertical apertures 11 and also formed through the jaw 8 are the plurality of vertical apertures 12 registering with the apertures 11, and for maintaining the jaws 7 and 8 in closed position the outer end of the handle 3 is 100 formed with the annular groove 13 and the knob 14 while the handle 4 is provided with the flattened and transversely apertured end 15 and in which is mounted the ring 16, which ring 16 is seated in the groove 13 105 of the handle 3 and retained in the groove 13 by the knob 14 when the handles 3 and 4 are forced to closed position.

Passing through the apertures 11 of the arm 7 from the upper side thereof and 110 through the apertures 12 of the arm 8 from the under side thereof are the cords or

snares 17, 18 and 19 of any suitable and desired lengths and having their end portions which pass through the apertures 12 of the arm 8 secured therein as by the knots 5 20 or other suitable securing means, the opposite ends of the cords or snares 17, 18 and 19 may extend for any desired and suitable distance rearwardly or in the direction of the handles 3 and 4.

10 The operation of the device will be briefly described as follows:—

When employing the device the operator forces the handles 3 and 4 inwardly toward each other and passes the ring 16 over the 15 knob 14 and into the groove 13 for locking the handles together and this operation forces the jaws 7 and 8 inwardly toward each other with their outer ends in close contact with each other which is obtained 20 by the inward deflection of the jaws 7 and 8 toward each other and the cords or snares 17, 18 and 19 are drawn rearwardly and taut until the operating end of the instrument assumes the position shown in Fig. 2, with the 25 exception that the ends of the jaws 7 and 8 are in close contact with each other. The instrument is now inserted in the vagina of the animal and along the left side thereof to the os uteri or mouth of the womb, and 30 if necessary into the uterus or the womb, or in other words until the head of the fetus has been reached with the arms 7 and 8 at one side of the head of the fetus. The ring 16 of the handle 4 is now released from 35 its engagement with the knob 14 of the handle 3 and the handles 3 and 4 forced apart sufficiently for separating the jaws 7 and 8 a sufficient distance apart so that the arm 7 will pass over the head of the fetus 40 and the arm 8 will pass beneath the head of the fetus when the instrument is manipulated laterally for passing the arms 7 and 8 to the opposite side of the vagina with the 45 cords or snares 17, 18 and 19 engaging one side of the head of the fetus and being drawn through the respective apertures 11 of the jaw 7 and at this stage the handles 3 and 4 are now forced together and the ring 16 of the handle 4 is positioned in locked en- 50 gagement with the knob 14 of the arm 3. This second closing of the handles 3 and 4 of the instrument causes the jaws 7 and 8 to be again closed in close contact with each other and at the same time the cords or 55 snares 17, 18 and 19 are further drawn or fed through the apertures 11 of the arm 7 with the result that the loops 21, 22 and 23, clearly shown in Fig. 3, of the respective cords or snares 17, 18 and 19 are formed 60 and with the loop 21 embracing the nose of the fetus for holding the same straight, the loop 22 embracing the head of the fetus

approximately at its forehead and the loop 23 embracing the head of the fetus just back of the ears, and thereafter the respective 65 cords or snares 17 and 18 are held sufficiently taut by the fingers of the operator and in a manner so that when the instrument is withdrawn the fetus may be safely and readily delivered and without any injury thereto in view of the fact that by the provision of the triple loops for distributing the strains to a multiplicity of points and at such points where injury to the head 70 of the fetus is less likely to occur, such 75 injury is avoided.

It is of course understood that this instrument may be made of any suitable size and material and while primarily designed for operating upon sows the same can be 80 varied in size and construction to adapt the instrument to a wide range of use, while I preferably employ three cords or snares the same may be increased if desired but not 85 diminished.

Having described my invention, what I claim as new and desire to secure by Letters Patent, is:

1. An obstetrical instrument comprising 90 pivotally connected members provided with a plurality of apertures at different distances from their pivot, and snaring strands secured at one end in the apertures in one jaw and having their free ends extended through the apertures in the other jaw. 95

2. An obstetrical instrument, comprising 100 two counterpart members pivotally connected together and provided with handles, apertured jaws upon the forward end of said counterpart members, snaring strands passing through said apertures, the forward ends of said snaring strands being secured in the apertures of one of said jaws and passing through the opposite jaw, and locking means 105 upon the rear ends of said handles.

3. An obstetrical instrument, comprising 110 two counterpart arms, flattened and obliquely disposed members at the rear ends of said arms and pivotally connected together, handles extending from said flattened and obliquely disposed members, inwardly deflected apertured jaws upon the forward ends of said arms, snaring strands secured to one jaw and passing through said apertures in the opposite jaw, and means upon the rear ends of said handles for maintaining said jaws in closed position. 115

In testimony whereof I have signed my name to this specification in the presence of two subscribing witnesses.

MATHEW J. SHERIDAN.
